CLAIM

The ornamental design for a cell phone housing, as shown and described.

DESCRIPTION

FIG. 1 is a front elevational view of the cell phone housing showing my new design in the closed position.

FIG. 2 is a front elevational view in the closed position.

FIG. 3 is a right side elevational view in the closed position.

FIG. 4 is a bottom plan view in the closed position.

FIG. 5 is a left side elevational view in the closed position.

FIG. 6 is a back elevational view in the closed position.

FIG. 7 is a top plan view in the closed position.

FIG. 8 is a front elevational view in the open position.

FIG. 9 is a right side elevational view in the open position.

FIG. 10 is a bottom plan view in the open position.

FIG. 11 is a left side elevational view in the open position.

FIG. 12 is a back elevational view in the open position.

FIG. 13 is a top plan view in the open position.

FIG. 14 is a front elevational view in the open position.

FIG. 15 is a right side elevational view in the open position.

FIG. 16 is a bottom plan view in the open position.

FIG. 17 is a left side elevational view in the open position.

FIG. 18 is a back elevational view in the open position; and,

FIG. 19 is a top plan view in the open position.

The broken line showing of the human hand in FIG. 1 is directed to environment and is for illustrative purposes only; the broken lines form no part of the claimed design.
